[57] CLAIM

An ornamental design for a recycling bin, as shown and described.

DESCRIPTION

FIG. 1 is a front perspective view of the recycling bin; FIG. 2 is a front elevational view thereof;

FIG. 3 is a side elevational view thereof as seen from the right hand side of FIG. 1, with the left hand side view being a mirror image thereof;

FIG. 4 is a top plan view thereof; and,

FIG. 5 is a rear elevational view thereof.
